UNITED STATES PATENT OFFICE.

OTTO PETERMANN, OF GROTON, NEW YORK, ASSIGNOR TO STANDARD TYPEWRITER COMPANY, OF GROTON, NEW YORK, A CORPORATION OF NEW YORK.

BAR MECHANISM FOR TYPE-WRITING MACHINES.

1,081,141.

Specification of Letters Patent.

Patented Dec. 9, 1913.

Application filed February 16, 1910. Serial No. 544,209.

To all whom it may concern:

Be it known that I, OTTO PETERMANN, a citizen of the Republic of Switzerland, and a resident of Groton, county of Tompkins, 5 and State of New York, have invented certain new and useful Improvements in Bar Mechanism for Type-Writing Machines, of which the following is a full, clear, and exact description.

10 This invention relates more particularly to means for hanging the type-bars of visible or front-strike typewriting machines.

The primary object of the invention is to provide simple and efficient hangers each 15 adapted to individually hold a type-bar so that said type-bar and the hanger may be removable, and so to construct the hanger that the parts comprising the same may be adjusted in the direction of wear without 20 taking the parts off the machine or the type-bar supported thereby detached from said hanger.

Another object of the invention is to provide a type-bar and hanger having relatively large bearing surfaces to secure proper alinement, and to construct the bearing surfaces in such a way that there will be very little friction.

Other objects of the invention are to provide hangers for type-bars which are substantially dust-proof yet permit the bearing and wearing surfaces to be properly lubricated; to provide hangers each adapted to hold a single type-bar and so formed as 5 to assume a curved or arc-like arrangement when placed in position, and to provide simple and effective adjusting means adapted to be operated from without the machine to permit the parts of each hanger to be adjusted quickly in the direction of wear and each hanger to be moved vertically of the machine frame for alining purposes.

A further object of the invention is to provide a hanger in which practically all 45 the parts may be stamped from sheet metal, and to provide hangers which may be used in connection with various forms and constructions of typewriting machines.

With these and other objects in view, the 50 invention will be hereinafter more particularly described with reference to the accompanying drawings, which form a part

of this specification, and will then be pointed out in the claims at the end of the description.

55

In the drawings, Figure 1 is a fragmentary vertical section of a typewriting machine, showing one form of my invention applied thereto. Fig. 2 is an enlarged vertical section of one of the hangers or brackets taken on the line II—II of Fig. 1, showing also one of the hangers in front elevation. Fig. 3 is an enlarged fragmentary side elevation of one end of the type-bar. Fig. 4 is a sectional plan view of one of the type-bars, taken on the line IV—IV of Fig. 3. Fig. 5 is a sectional plan taken on the line V—V of Fig. 2. Fig. 6 is a vertical section showing a slightly different form of means for pivotally supporting the type- 70 bars. Fig. 7 is an enlarged fragmentary section, showing a different form of means for taking up the wear. Figs. 8 and 9 are sections showing different means for pivotally holding the type-bar between the 75 hanger members; and Fig. 10 is an elevation, showing the arrangement of a plurality of hangers looking at the rear thereof.

The frame 10 has a plurality of pivotally held key-levers 11 supported thereon 80 which may be normally forced in one direction by springs 12, and at their inner ends are connected by links 13 to the type-bars 14. The type-bars 14 have type-heads 15 at their outer ends, and said heads, when the 85 key-levers 11 are depressed, are forced upward against the platen 16, the latter being suitably supported on a carriage 17 or otherwise held on the machine. All of these parts may be of the usual or of any preferred 90 construction and arranged in any desired way.

Each type-bar 14 is held to a bracket or hanger 18, there being an individual hanger for each type-bar. This hanger 18 comprises two members 19 and 20. The member 19 may be made somewhat heavier than the member 20 and has an angular or flange portion 21 which is adapted to rest against the back plate or member 22 of the machine 100 frame, and said angular portion is provided with threaded openings 23 which are adapted to be engaged by the threaded ends of screws 24 to removably hold the hanger to

the machine frame, and if the openings through the machine frame are slightly larger than the screws 24, a vertical adjustment of said hanger may be secured. 5. The flange or angular portion 21 is tapered, to cause the hangers when in position to assume a segmental or curved arrangement as shown in Fig. 10.

The member 20 is substantially rectangular in form and has an off-set portion 25 forming a space 26 between the said member and the member 19. This member 20 has a flange or part 27 which is fastened by a screw 28 or otherwise to the member 19, 15 and has a part 29 which will yield or spring and permit the off-set portion 25 to move toward the member 19. At the upper portion of the member 20 is a flange 30 through which is an opening, and passing through 20 the opening is a threaded stem 31 of a bolt 32, the end of which engages a threaded opening in the upper portion of the member 19. The head of the bolt or adjusting device 32 may be hexagonal so that a wrench 25 or tool may be made to engage said head and rotate the bolt to force the portion 25 of the member 20 inward toward the member 19. As will be seen, the portion 25 extends outward beyond the flange 30, so that 30 when two brackets are placed side by side, a space will occur between the same for the head of the bolt 32 sufficient for a thin wrench to be inserted for adjusting purposes.

35. A head or pivoting end 33 is provided on each type-bar and this head serves to form a bearing portion for the type-bar in the space 26 between the members 19 and 20. The head 33 is circular in form and of a relatively large diameter, and has an annular bearing rib 34 formed on one side thereof. The rib or bearing 34 is integral with the body of the type-bar, and in forming the rib 40 the body of the type-bar is depressed or tapered, at 35, from the rib gradually to the thickness of said body. A tapered opening 36 is formed in the head 33 substantially centrally thereof when the type-bar is made and said opening is formed by forcing a part 45 of the body of the metal outward, as at 37. This serves to provide an extended opening which is adapted to receive a projecting pintle 38 formed as a part of the member 20. The pintle or bearing 38 may be formed by 50 forcing the metal inward and the outer surface thereof may be ground if desired to properly fit the opening 36 in the head of the type-bar, the member 19 being also provided with an opening 38 if desired adjustment to the projecting part 37 so that the 55 said part 37 may extend into said opening without interfering with the movement of the type-bar, and to permit proper adjustment of the member 20 and type-bar.

As will be seen, the head 30 with the rib 65 or portion 34 forms a relatively large bearing surface with very little friction, and at the same time said bearing rib or surface may be forced into engagement with the inner surface of the member 19 in case of wear, 70 by rotating the bolt 32 which will force the projecting part 38 into the opening 36 thus taking up any wear or lost motion that might occur. The bolt 32, screw 28, and pivot for the type-bar are in alinement so 75 that the wear may be taken up evenly and without removing the hangers. It will be seen also that the pivot bears on one side of the type-bar only while a relatively large concentric and plane bearing surface is provided on the other side of said bar.

The parts so far as the openings, the type-bar and the members of the hanger are concerned may be stamped from sheet metal, and when being stamped to provide an 85 opening for the screw 28, the member 20 at the flange or part 27 may be depressed, to form two projections 39 serving as dowel pins which are adapted to fit into openings 40 in the member 19.

In Fig. 6, the construction is substantially the same as that already described except that instead of the part 38 which is forced from the body of the member 20, a pin 41 is provided which has a beveled end, as at 42, to fit into the tapering opening 36 of the type-bar end or head 33, and in this construction and also in the form already described, an overhanging lip 43 is provided on the member 20 which is adapted to fit 100 over the upper edge of the member 19 and which prevents dirt and particles caused by the eraser from falling into the opening or space between the members 19 and 20.

Fig. 7 shows a construction substantially 105 the same as that of the other figures except as to the means for adjusting the two members 19 and 20 relatively with respect to each other. In this form, the member 19 is provided with a flange 44 in which is a tapered opening 45 and this opening is adapted to be engaged by the tapered end 46 of a screw or bolt 47, the latter being provided with a head 48 for engagement by a screw driver, or the said head may be otherwise 110 formed to be operated in any desired way. When the bolt 47 is rotated, the tapered end 46 of said bolt by engaging with one side of the tapered opening 45 will force the member 20 inward to adjust and hold the type-bar 115 properly against the member 19.

The construction shown in Fig. 8 provides an effective means for pivotally supporting the type-bar. The type-bar head 33 has a tapered opening 49 which is opposed to a 120 tapered opening 50 in the hanger member 20, and in said opening is a ball 51. This ball is adjustable with the member 20 and serves

as a pivot for the type-bar, otherwise the hanger may be constructed as already described.

In Fig. 9, as in the other views, the hanger 5 may be constructed and the members adjusted in any desired way. Here the pivot 52 is in the form of a pin carried by the member 20, and said pin has its inner end hemispherical or ball-like which enters a 10 tapered opening in the type-bar head 33.

From the foregoing, it will be seen that simple and efficient means are provided whereby a number of type-bars may be independently supported in hangers so as to 15 be removable; that said hangers are simple in construction and permit proper adjustment to compensate for wear and to keep the type of the type-bars in proper alignment; that by constructing the hangers in the manner described, the cost of assembling the type-bars and making the machine is substantially reduced; that the type-bars may have a relatively large bearing surface with a small amount of friction; that simple and 20 efficient means is provided for adjusting the parts of the hangers individually without removing the hangers or without removing the type-bars therefrom; that said hangers are 25 adapted for use in various classes of machines; that simple means is provided for pivotally holding the type-bars; that substantially the entire hanger may be stamped from sheet metal and thereby require very little hand work, and that a hanger is provided which is dust-proof and which may be 30 easily lubricated.

Having thus described my invention, I claim as new and desire to secure by Letters Patent:—

40 1. The combination of a hanger, and a type-bar having a pivotal connection in said hanger at the central portion thereof and on one side only and a relatively large and concentric plane surface bearing directly 45 against the hanger on the opposite side of said type-bar.

2. The combination of a hanger, and a type-bar having a pivotal connection in said hanger at the central portion thereof and 50 on one side only, and a relatively large and concentric rib forming a plane surface bearing directly against the hanger on the opposite side only of said type-bar.

3. The combination of a hanger having 55 two relatively adjustable members, a type-bar having a central opening, a pivot entering said opening and bearing on said bar at one side only, and a relatively large and concentric surface bearing directly against the hanger on the side of said type-bar opposite the pivot, and means in alignment with the pivot whereby the two members 60 may be adjusted to take up any wear.

4. The combination of a hanger having

two members, a type-bar having a central 65 opening, a pivot entering said opening and bearing on said bar at one side only and a relatively large concentric rib on the type-bar forming a bearing surface between the bar and the hanger on the side of said type-bar opposite the pivot, and means in alignment with the pivot whereby the two members 70 may be adjusted to take up any wear.

5. The combination of a hanger having two opposed members, a type-bar, a pivot 75 for said type-bar bearing against said bar at one side only and a relatively large and concentric surface bearing directly against the hanger on the side of said type-bar opposite the pivot, and means whereby the 80 two members may be adjusted to take up any wear.

6. The combination with a type-bar having a head provided with an annular rib on one side only, of a hanger having two 85 opposed members forming a bearing space for said type-bar head, said rib bearing directly against one of said members, and means whereby the bearing portion of said members may be moved relatively with respect to each other in the direction of wear 90 from one end of said hanger.

7. The combination of a type-bar having a relatively large and annular bearing rib at one end and on one side only, a hanger 95 having two opposed and relatively movable plate-like members against one of which said rib directly bears, and means for pivotally holding the type-bar on the side opposite the rib, said members forming a bearing space for the end of the type-bar and adjustable toward each other by means located at one end of said hanger.

8. The combination of a hanger having two plate-like members adjustable at one 105 end only of said hanger to force the members toward each other, and a type-bar located between the members and pivoted to one member on one side only substantially central of its supporting end and having a 110 flat bearing directly against the other member.

9. The combination with a plurality of type-bars, of a plurality of hangers having opposed members forming a space between 115 them, means for holding the members of each hanger at one end, means for adjusting the members at the opposite end, and means for supporting one end of the type-bar in each hanger, the fastened and adjustable 120 ends and pivoting supporting means being in alignment.

10. The combination with a hanger having two members forming a space between the same, one of said members being held 125 at one end thereof and adjustable with relation to the other member at the other end thereof, and a type-bar having a substan-

4

tially circular end located within the space formed between said members and bearing directly against one of the members on one side, and means located on the other side for pivotally holding the type-bar to the other member.

11. The combination with a hanger having two plate-like separable members forming a space between the same, one of said members being held rigidly at one end thereof and adjustable with relation to the other member at the other end thereof, and a type-bar pivotally supported on one member within the space formed between said members and having a flat bearing surface bearing directly against the face of the other member and on the side opposite the pivot.

12. The combination with a plurality of type-bars, each having an annular projecting bearing, of a plurality of independent hangers each having opposed plate-like separable members forming a space between them, means for holding the members of the hangers at one end, a bolt for adjusting the members at the opposite end, and means for pivotally supporting one end of a type-bar in each hanger.

13. A type-bar having an annular bearing rib and a depressed part forming a tapered opening, and a hanger having an integral tapered projection fitting said opening and forming a pivot for said bar.

14. A type-bar hanger having two plate-like members fastened together at one end and relatively adjustable at the other end and having means for pivotally supporting a type-bar between them, the fastened and adjustable ends and pivoting supporting means being in alinement.

15. A hanger for type-bars, comprising a member having an angular portion adapted to be secured to a part of the machine frame, a second member having an off-set portion providing a space between the same and the first-mentioned member and having two flanged portions, one of which is held rigidly to the first-mentioned member, means for adjustably holding the other flanged portion to the first-mentioned member to cause the off-set portion to move toward the same, a type-bar having an annular rib forming a bearing surface and a depressed portion forming a tapered opening, an adjusting bolt for forcing one member toward the other, and an integral projection forced from the off-set portion of one of the members and adapted to fit into the tapered opening of the type-bar.

16. A hanger for type-bars, comprising a member having an angular portion adapted to be secured to a part of the machine frame, a second member having an off-set portion, providing a space between the same and the first-mentioned member and having

two flanged portions, one of which is held rigidly to the first-mentioned member, means for adjustably holding the other flanged portion to the first-mentioned member to cause the off-set portion to move toward the same, and a type-bar pivotally held between said members.

17. A hanger for type-bars, comprising a member adapted to be secured to a part of the machine frame, a second member having an off-set portion providing a space between the same and the first-mentioned member and having two flanged portions, one of which is held rigidly to the first-mentioned member, and means for adjustably holding the other flanged portion to the first-mentioned member to cause the off-set portion to move toward the same.

18. A hanger for type-bars, comprising a member having an angular portion adapted to be secured to a part of the machine frame, a second member having an off-set portion providing a space between the same and the first-mentioned member and having two flanged portions, one of which is held rigidly to the first-mentioned member, means for adjustably holding the other flanged portion to the first-mentioned member to cause the off-set portion to move toward the same, a type-bar having a depressed portion forming a tapered opening, means for forcing one member toward the other, and an integral projection forced from the off-set portion of one of the hanger members and adapted to fit into the tapered opening of the type-bar.

19. The combination with a hanger having two members forming a space between the same, one of said members being of spring material and held rigidly at one end thereof and adjustable with relation to the other member at the other end thereof, and a type-bar supported within the space formed between said members, the support for the type-bar and the rigid and adjustable ends of the hanger being in alinement.

20. The combination with a hanger having two plate-like separable members forming a space between the same, one of said members being held rigidly at one end thereof and adjustable with relation to the other member at the other end thereof, and a type-bar pivotally supported on said movable member within the space formed between said members, the pivot for the type-bar, the rigid end and the adjustable end being in alinement.

21. The combination with a hanger comprising two relatively adjustable members formed of sheet metal and providing a space between the same, one of said members having openings therein and the other member having one end fastened rigidly to the first-mentioned member and having projec-

tions extending therefrom forming dowel pins to enter said openings, and a type-bar pivotally held in the space between said members and supported by one of said members.

22. The combination with a support, of a hanger, comprising two relatively adjustable members formed of sheet metal and providing a space between the same, one of said members having openings therein and the other member having integral projec-

tions extending therefrom forming dowel pins to enter said openings, and a type-bar pivotally held in the space between said members.
